UNITED STATES PATENT OFFICE.

RUSH McCARGAR, OF SEATTLE, WASHINGTON.

DESIGN FOR A CASING FOR A STAGE FLOOD-LIGHT.

55,189.

Specification for Design.

Patented May 18, 1920.

Application filed December 13, 1919. Serial No. 344,602. Term of patent 7 years.

To all whom it may concern:

Be it known that I, RUSH McCARGAR, a citizen of the United States, whose post-office address is 1006 Third avenue, in the city of Seattle, county of King, and State of Washington, have invented a new, original, and ornamental Design for a Casing for a Stage Flood-Light, of which the following is a specification, reference being had to the accompanying drawings, forming a part thereof.

Figure 1 is a perspective view in front elevation of a casing for a stage flood light showing my new design;

Fig. 2 is a perspective view in side elevation of the same; and

Fig. 3 is a view in rear end elevation of the same.

I claim—

The ornamental design for a casing for a stage flood light, as shown.

RUSH McCARGAR.
